Henry L. Boppel, Dayton, Ohio

Application July 23, 1953, Serial No. 26,113

Term of patent 14 years

(Cl. D52—1)

To all whom it may concern:

Be it known that I, Henry L. Boppel, a citizen of the United States of America, residing at Dayton, in the county of Montgomery, State of Ohio, have invented a new, original, and ornamental Design for a Gauging Device for Measuring or Comparing Sizes, Dimensions, and the like, of which the following is a specification, reference being had to the accompanying drawing, forming a part hereof.

In the drawing:

Figure 1 is a front perspective view of a gauging device for measuring or comparing sizes, dimensions, and the like showing my new design.

Figure 2 is a perspective view of the same as viewed from the side.

Figure 3 is a top view, and
Figure 4 is a sectional view as taken along line 4—4 of Figure 1.

I claim:

The ornamental design for a gauging device for measuring or comparing sizes, dimensions, and the like, substantially as shown.
